UNITED STATES PATENT OFFICE.

WILLIAM H. PRITCHETT, OF THE UNITED STATES MARINE CORPS.

PUNCTURE-PROOF LINING FOR PNEUMATIC TIRES.

1,302,970.

Specification of Letters Patent.

Patented May 6, 1919.

Application filed October 3, 1918. Serial No. 256,696.

To all whom it may concern:

Be it known that I, WILLIAM H. PRITCHETT, Major, U. S. M. C., a citizen of the United States, stationed at Santiago, in the Dominican Republic, have invented certain new and useful Improvements in Puncture-Proof Linings for Pneumatic Tires; and I do hereby declare the following to be a full, clear, and exact description of the invention, such as 10 will enable others skilled in the art to which it appertains to make and use the same.

My present invention relates to improvements in puncture proof pneumatic tires, and it is intended to provide a resilient tire 15 in which the outer casing or shoe may be made either of standard type, or of thinner material if desired, and the usual inner tube may be used; and this tube may be protected against perforation by a removable armored 20 lining which constitutes the essence of my present invention.

This armored lining comprises a metal framework, consisting of a pair of split stay rings to which a series of overlapping thin 25 metal strips or ribbons are attached, between which metal ribbons one or more layers of canvas, or other suitable flexible or textile material, may be placed, and the whole metal frame is engaged in a suitable covering of 30 canvas, or other suitable flexible material, the edges of which flexible covering project inward over the outer surface of the rim, and thus a suitable bearing surface for the inner tube, which prevents the inner tube 35 from being forced under the edges of the stay rings, when expanded, is provided.

My invention will be more fully understood after reference to the accompanying drawings, in which similar parts are indicated by similar reference symbols throughout the several views, and in which:

Figure 1 shows a cross section through the metal rim and outer casing and armored lining of the tire, the inner tube being omitted 45 for the sake of clearness in the drawings.

Fig. 2 is a diagram showing the overlapping metal plates or ribbons, the width of these parts being exaggerated to illustrate the overlapping feature, and all of the textile fabric used in the construction of the 50 armored lining being removed.

Fig. 3 is a detail view showing a portion of one of the split rings used in the construction of the armored lining.

Fig. 4 shows on a smaller scale one of the metal plates or ribbons used in forming the

loops, the plate being shown in the flat position before being bent up to the shape shown in Figs. 1 and 2.

Fig. 5 is a perspective view of the completed armored lining in the contracted position, ready for insertion into the outer casing; and

Fig. 6 shows the armored lining in the expanded position, but with the tire casing 65 omitted, and parts being broken away.

A represents the metal rim of the wheel, which rim is shown only in Fig. 1. Any suitable type of demountable rim may be adopted in connection with my invention. 70

B shows the outer casing or shoe of the tire, and C represents the armored lining which is composed of the inner lining or cover 1 of canvas, projecting inwardly toward the middle of the rim, as at 1^a, and 75 inside of which, near its ends, are the split stay rings 2, perforated as at 2^a, and preferably countersunk to receive the heads of the rivets 3. These stay rings are split diagonally, as at 2^b, so that they may expand 80 when the tire is inflated, and thus enable the armored lining to conform to the inner shape of the inflated tire; and therefore the armored lining will not interfere with or detract from the resiliency or pneumatic qualities of the tire. The split also enables the armored lining to be contracted as shown in Fig. 5, and thus enables its insertion into the outer casing B, Fig. 1.

Secured to the stay rings 2 are the metal 90 strips or ribbons 4 and 4^a of the general construction shown in Fig. 4, in which each strip is perforated, as at 4^b, to engage the rivets 3, (see Figs. 1, 5 and 6), and tapers from the center 4^c toward the ends, so that 95 the overlapping portions may be of substantially the same width as shown in Fig. 2.

These metal strips overlap, as shown in Fig. 2, and are preferably bent into the shape shown in Fig. 1 before being attached 100 to the stay rings 2.

Between these strips 4 and 4^a I preferably provide one or more layers of canvas, or other suitable textile material, so as to prevent the parts from rubbing on each other, 105 and this textile material is preferably treated, before being inserted, with soap-stone, graphite, or other suitable lubricant.

Exterior to the outer strips 4^a is the covering 5, of canvas or other suitable textile 110 material, the inner edges of which project inward toward the middle of the rim, as

shown at 5^a in Fig. 1. The outer portion and inner portion of this canvas covering are sewed together at the edges of the stay rings after being placed in position on the armored lining.

- When completed, the canvas covering of the armored lining should be treated both outside and inside with graphite, soap-stone, or other suitable lubricant, before being 10 sewed on to the armored lining, so as to lessen the friction between the parts. This is more especially important on the inside when the inner tube is inserted and inflated, and the tire is in use on the road.
- 15 The overlapping metal strips 4 and 4^a may be made of steel or other resilient material, and preferably thick enough only to prevent the penetration into the chamber inside of the armored lining, of a nail, tack, particles of glass, or other objects, which cause punctures to pneumatic tires.

Moreover, this armored lining will protect the tire against blow-outs, as the outer casing may be worn or cut through for several 25 inches and no blow-out will occur, the pressure of the air in the inner tube being taken by the armored lining at the worn or cut place.

The purpose of the textile fabric used in 30 the armored lining between the two layers of metal ribbons is to protect the metal ribbons from rubbing against each other. The purpose of the canvas covering is to protect the inner tube and the outer casing from being 35 rubbed by the metal strips or ribbons, as each ribbon will successively have a slight motion when it reaches the point of contact with the ground when the tire is in use. The purpose of the extension of the edges 40 over the surface of the rim, as at 1^a and 5^a, Fig. 1, is to protect the inner tube from being cut by being forced under the stay rings, as these stay rings are slightly distended away from the rim of the wheel, as happens 45 when the tire is inflated.

When the armored lining is inserted in the outer casing of the tire, the inner tube may

be inserted, and the tire complete may be mounted upon the rim and the inner tube inflated in the usual way.

50

By having the metal framework of the armored lining constructed as shown, the necessary resiliency to the tire as a whole is maintained, and yet the inner tube is effectively protected against puncture from 55 without.

While I have shown the invention in the preferred form as now understood by me, it will be obvious that various modifications might be made in the combination and arrangement of parts which could be used without departing from the spirit of my invention, and I do not intend to limit the invention to such details of construction except as particularly pointed out in the claims.

65

Having thus described my invention, what I claim and desire to secure by Letters Patent of the United States is:—

1. In an armored pneumatic tire, the combination with the outer casing, of a removable armored lining for said casing comprising a pair of split stay rings, a series of overlapping thin strips of resilient metal bent in the form of loops to fit the interior of said casing, said strips having their opposite ends secured respectively to said split stay rings, and a sheathing of textile fabric inclosing said loops and said rings, substantially as described.

70

2. In an armored pneumatic tire, the combination with the outer casing, of a removable armored lining for said casing comprising a pair of split stay rings, a series of overlapping thin strips of resilient metal bent in the form of loops to fit the interior 85 of said casing, said strips having their opposite ends secured respectively to said split stay rings, a layer of textile fabric interposed between said overlapping loops, and a sheathing of textile fabric inclosing said 90 loops and said rings, substantially as described.

80

In testimony whereof, I affix my signature.
W. H. PRITCHETT.
